UNITED STATES PATENT OFFICE.

CURTIS E. SMITH, OF ST. JOSEPH, MISSOURI.

MITER JOINT.

1,416,901.

Specification of Letters Patent. Patented May 23, 1922.

Application filed May 31, 1921. Serial No. 473,821.

To all whom it may concern:

Be it known that I, CURTIS E. SMITH, a citizen of the United States, residing at St. Joseph, in the county of Buchanan and State of Missouri, have invented certain new and useful Improvements in Miter Joints, of which the following is a specification.

This invention relates to miter joints, and particularly to a joint adaptable for use in joining the members of a gable or cornice, on stairways, house trim, and in other carpentry and joinery work.

An object is to provide a miter joint in which a heel is let into the miter thus preventing slipping when toenailing and doing away with the necessity of first gluing or clamping the two members.

A further object resides in so constructing the miter that the two members can not slip and will need no nailing when they are placed to abut in a corner, as in the case of a baseboard.

A still further object is to provide a joint which while constructed to prevent slipping and give a solid abutment between the two members is yet so constructed that on its outer or finished side it presents the appearance of the usual miter joint.

Another object lies in so cutting and associating the members that a broken joint is formed which will be substantially air and water tight when the members are secured together and will eliminate the necessity of resorting to the present expedient of using glue blocks to back up and strengthen the corner.

With these and other objects in view which will be apparent from the drawings, specification and claims this invention includes certain novel features of construction and combinations of parts which will now be set forth.

In the drawings:

Figure 1 is a plan view showing the joining of two members in accordance with my invention.

Fig. 2 is a perspective view showing the two members.

Fig. 3 is a perspective view illustrating the formation of the joint on a diagonal line.

Fig. 4 is a perspective view to better disclose the cutting of the two members in Fig. 3.

Fig. 5 is a plan view illustrating the adaptation of the joint for frames and the like.

Fig. 6 is a perspective view to better show the formation of the two members in Fig. 5.

My invention contemplates the association of two members by the use of a miter joint, and this joint can be employed in the construction of gables, hip joints, eaves, cornices, and the like; in the interior trim of buildings, and in trimming out stairways and associating trim or moldings of any character; in making picture and screen frames, and connecting the members of refrigerator and like cases where air or water tight joints are desired; and, in fact in any connection where an ordinary miter joint might be used and in some places where the usual miter will not be satisfactory.

In the embodiment shown in Fig. 1 the members 1 and 2 have their ends cut to form the miter faces 3 and 4. An offset heel 5 is cut on the member 1 to give an abutment face 6 substantially parallel with the outer face of this member and an abutment face 7 at right angles. The member 2 is notched 8 in its miter face 4 to receive the offset heel 5 and has abutment faces 8 and 9 which fit and bear against the abutment faces 6 and 7.

As shown in Fig. 2 the offset heel and the notch are formed along the extent of the miter faces and a broken joint is thus provided when the parts are assembled as illustrated in Fig. 1. The contact of the abutment faces will prevent the joint from slipping when toenailing to secure the members.

In the adaptation in Figs. 3 and 4 the joint is formed in a manner substantially identical with the showing as described, except that the pieces 10 and 11 are cut across diagonally at 12, the miter faces 13 and 14 and the offset heel 15 and notch 16 being cut to follow the diagonal line. This cut may be employed in gables, cornices, eaves, and the like, and in joining the risers of stairways.

The joint illustrated in Figs. 5 and 6 is particularly adapted for joining the members of picture, screen, or other frames, for window and door trim, and in other connections where the appearance of the usual miter joint is desired on the finished side.

In this adaptation the members 17 and 18 are formed with the miter faces 19 and 20, which extend entirely across the members on the finished side. On the rear side of 5 member 17 a notch 21 is cut at the inner corner of the miter face, this notch having the angularly disposed abutment faces 22 and 23. An offset heel 24 is provided on the miter face 20 of member 18 and has abutment faces 25 and 26 which contact with 10 the abutment faces of the notch 21.

While I have herein shown and described only specific embodiments of my invention and have mentioned only certain possible 15 adaptations in use, it will be appreciated that my improved miter joint may be formed in a number of different ways for use in various connections, in view of which I do not limit myself to such specific details as 20 herein set forth, but may resort to any practical modifications falling within the scope of the invention as defined in the appended claims.

I claim:—

1. In a miter joint, a pair of members, the 25 end of one member being provided with two surfaces disposed in intersecting planes and extending unbroken from the line of intersection to the opposite sides of said first member whereby a mitered end having a 30 heel is provided, the end of the second member being provided with two faces disposed in intersecting planes and connected at their inner ends by a third plane surface, the first two of the second set of surfaces extending unbroken from the connecting surface to the opposite sides of the second member, whereby the second member is provided with a mitered end having abutment faces to receive the heel of the first 40 member.

2. A structure as defined in claim 1, wherein the abutment faces are triangular in contour.

In testimony whereof I affix my signature. 45
CURTIS E. SMITH.
